UNITED STATES PATENT OFFICE.

JOHN W. SWALES, OF OAKLAND, CALIFORNIA.

AEROPLANE.

1,150,233.

Specification of Letters Patent. Patented Aug. 17, 1915.

Application filed February 12, 1914. Serial No. 818,359.

To all whom it may concern:

Be it known that I, JOHN W. SWALES, a citizen of the United States, residing at Oakland, in the county of Alameda and State of California, have invented certain new and useful Improvements in Aeroplanes, of which the following is a specification.

One of the objects of this invention is to provide an aeroplane with angularly disposed longitudinally extending fixed stabilizing and sustaining plane surfaces which will greatly extend the stabilizing surface over and above any construction now known to me.

A further object of the invention is to hang a platform, which also functions as a plane surface, from the plane body comprising the stabilizing and sustaining planes and disposing the weight of the engine and the operator's weight on opposite sides of the center of mass in such a manner as to equalize the load and assist in rendering the aeroplane stable in flight.

Further objects and features of the invention will be more fully described in connection with the accompanying drawings and will be more particularly pointed out and ascertained in and by the appended claims.

In the drawings: Figure 1 is a view in side elevation illustrative of one embodiment of my invention. Fig. 2 is a plan view with portions of the fixed plane omitted. Fig. 3 is a sectional view on line 3—3 of Fig. 1. Fig. 4 is a rear view of a portion of the fixed stabilizing plane structure, in perspective, showing a stabilizing rudder and a portion of the operating means therefor. Fig. 5 is a sectional view of an operating device for the stabilizing rudder, the steering rudder and the altitude rudder.

Like characters of reference designate similar parts throughout the different figures of the drawings.

As illustrated, my improved air-ship includes fixed planes 1, 2, 3 and 4, which extend upwardly, downwardly, and laterally, respectively, from a medial line of juncture of said planes which medial line intersects the center of mass and which extends longitudinally of the structure. The planes 1 and 2 function primarily as stabilizing planes whereas the planes 3 and 4 function primarily as lifting or sustaining planes. As will be seen more particularly by refer-

ence to Fig. 3, the stabilizing planes 1 and 2 are vertically disposed and extend upwardly and downwardly from the medial line of juncture 5 whereas the sustaining planes 3 and 4 extend laterally outwardly from the point of juncture 5 in a generally horizontal direction. I prefer to transversely curve the sustaining planes 3 and 4 from the point of juncture 5 upwardly and outwardly toward their edges 6 and 7 so that the outer edges 6 and 7 will lie somewhat above the medial point of juncture 5. The sustaining planes 3 and 4 are also curved longitudinally and their forward ends 8 curve downwardly and likewise their rearward ends 9 curve downwardly from the central portions 10 thereof.

In plan view, the sustaining planes 3 and 4 are generally oval in contour, and in side elevation, the stabilizing planes 1 and 2 are generally elliptical in contour and the stabilizing and sustaining planes are shown of substantially equal length and extending throughout the length of the body of the air-ship.

I provide a support for the operator and the prime mover which is preferably shaped to constitute a plane surface, and in the form shown, the platform is indicated at 11 and comprises an oval-shaped body in plan, an upwardly curved prow 12 and an upwardly curved stern 13. Wheels 14 are shown mounted on brackets 15 which are secured to the platform 11, and the latter is pendentally hung from the sustaining planes 3 and 4 by means of rods 16 and 17. Inasmuch as the upwardly bent prow 12 serves as an elevating surface, and inasmuch as this forward elevating surface merges into the body of the platform 11, it will be seen that that portion of the platform 11 between the wheels 14 will act as a sustaining plane so that the rods 16 and 17, during flight, will primarily function as a means for rigidly connecting the platform with the rigid plane structure, comprising the planes 1 to 4. When the air-ship is at rest, and is carried by the wheels 14, then the rods 16 and 17 will function as supporting rods for the rigid plane structure.

The platform plane is provided with a central opening 18 and is connected with the rigid plane structure in such close proximity that the lower stabilizing plane 2 projects through the opening 18 and extends below the platform plane 11 throughout a

portion of the length thereof. In addition to the pendant rods 16 and 17, I may connect the platform plane 11 with the stabilizing plane 2 by transverse brace members 19, 5 which may be connected with the plane 2 in any desirable manner, as will be more clearly seen by reference to Fig. 2. As shown, the braces 19 extend between the axles 20, of the wheels 14.

10 The oval platform plane 11 provides sufficient area, laterally of the stabilizing plane 2, for supporting various mechanisms which will now be described.

Propeller shafts 21 and 22 are mounted 15 in bearings 23 and 24, respectively, and extend in parallel relation with the longitudinal axis of the air-ship. On the ends of said shafts 24 and 22 I mount propellers 25 and 26 so that an air current will be drawn 20 between the platform plane and the sustaining planes 3 and 4 and on opposite sides of the lower stabilizing plane 2. A prime mover 27, which may be in the form of a gasoline engine, is connected by transmission 25 means such as sprocket chains 28 and 29, with shafts 21 and 22, respectively, as will be seen more clearly by reference to Fig. 2. The weight of the prime mover 27 is counterbalanced by the weight of the 30 operator whose seat is indicated at 30, and also by a steering operating device indicated as a whole at 31, which is in accessible operating proximity to the operator's seat 30.

An altitude rudder 32, is movable about a 35 horizontal axis, as indicated at 33, at the juncture of the forward ends of the sustaining and stabilizing planes. Operating cables 34 and 35, the former for lowering and the latter for raising the plane 32, are 40 connected therewith, as indicated at 36 and 37. Said operating cables 34 and 35 are trained about pulleys 38 and 39 and extend over pulleys 40 and 41 downwardly to an operating drum 42, about which they are 45 trained in opposite directions. The drum 42 is mounted upon a drum spindle 43 which is provided with a hand-wheel 44. A drum 45 is formed integral with a drum sleeve 46 which is rotatable on the spindle 43 and is 50 provided with a hand-wheel 47. A drum 48 is formed integral with drum sleeve 49 which is journaled in a bearing 50 mounted on uprights 51. A hand-wheel 52 is provided for turning the drum 48.

55 Rearwardly of the fixed plane structure I mount a stabilizing plane which is adjustable about a horizontal axis and which is indicated at 53. Plane 53 may be provided with a sleeve 54 rotatable about a spindle 55 60 projecting from the rigid plane structure, as shown more particularly in Fig. 4. Pulleys 56 and 57 are loosely mounted upon a stud 58 projecting rearwardly from the fixed plane 1 and cables 59 and 60 are connected 65 with the stabilizing plane 53 on opposite

sides of its axis, and extend about the pulleys 56 and 57 and downwardly therefrom over pulleys 61 and 62 from which they extend forwardly over pulleys 63 and 64 down to drum 45 about which the cables 59 and 60 are trained in opposite directions.

The air currents generated in the wake of the propellers are deflected by the rear deflecting portion 13 of the platform plane against the stabilizing plane 53 so that in 75 case the airship tilts from an upright position, it can be righted by tilting the stabilizing plane 53 so that pressure will be relieved on one under side thereof and increased on another under side thereof, the 80 under sides referred to being on opposite sides of the horizontal axis about which the plane is tilted.

A rear portion of the fixed stabilizing plane 1 is hinged, as at 65, to swing about a vertical axis to steer the aeroplane. This steering rudder is indicated at 66 and is provided with oppositely extending arms 67 and 68 to which controlling cables 69 and 70 are connected. The controlling cables 69 and 70 are trained about pulleys 71 and 72 and extend downwardly to drum 48 where they are wound thereabout in opposite directions.

Any suitable means may be provided for 95 locking the drums 42, 45 or 48 in adjusted positions if desired, such means being in the form of pawl and ratchet or suitable friction clutches, but as my invention does not pertain to this feature of the structure, 100 I have not thought it necessary to illustrate this feature in detail.

Propulsive thrust is imparted by means of the propellers and therefore it will be seen that an air current will be induced to 105 flow between the sustaining planes 3 and 4 and the platform plane 7, where it will be discharged rearwardly between the converging ends 9 and 13, of said planes. The fixed stabilizing plane 1 will be free from air 110 currents generated by the propellers to maintain the air-ship in a normal position, the fixed stabilizing planes 1 and 2 acting as air keels. Furthermore, resistance at the front of the machine is reduced to minimum by reason of the fact that the keels or stabilizing planes 1 and 2 present their front edges to the air and the upturned prow 12 serves to increase ascending action. 115 Altitude, however, is controlled by the altitude plane 32, primarily.

While I have herein shown and described one specific form of my invention, I do not wish to be limited thereto except for such limitations as the claims may import.

I claim:—

1. An aeroplane comprising in combination, substantially horizontal and vertical plane surfaces extending outwardly from a medial line of juncture, a carrying plane 120

- hung from said horizontal surface, and propellers mounted between said horizontal plane and said carrying plane.
2. An aeroplane comprising in combination, substantially horizontal and vertical planes of identical outline contour with respect to each other and extending outwardly horizontally and vertically from a medial line of juncture, a carrying plane hung from said horizontal plane, and propellers mounted between said horizontal plane and said carrying plane.
3. An aeroplane comprising in combination, substantially horizontal and vertical planes of oval outline extending outwardly from a medial line of juncture and rigidly connected to form a sustaining and stabilizing body, and a carrying plane swung from said horizontal plane.
4. An aeroplane comprising in combination, substantially horizontal and vertical planes extending outwardly from a medial line of juncture, the horizontal planes being arched transversely and longitudinally, a carrying plane swung from said horizontal planes, and propellers mounted between said horizontal planes and said carrying plane to cause the air to be directed against said horizontal planes and to give the proper propulsive movement.
5. An aeroplane comprising in combination, a rigid body composed of vertical planes extending upwardly and downwardly from a medial line of juncture and horizontal planes extending outwardly from said medial line of juncture and said planes being equal in length with respect to each other, and a carrying plane hung from said body and arched to extend its prow and stern ends toward said horizontal planes.
6. An aeroplane comprising in combination, a rigid body composed of vertical planes extending upwardly and downwardly from its medial line of juncture and horizontal planes extending outwardly from said line of juncture, a carrying plane hung from said body and extending in subjacent relation with respect to said horizontal planes, and propelling devices disposed on opposite sides of said downwardly extending plane and between said horizontal planes and said carrying plane.
7. An aeroplane comprising in combination, superposed horizontal planes converging toward each other at the stern, a propeller mounted to work between said planes for discharging a current between the con-

verging ends thereof, a vertically disposed plane extending longitudinally of said superposed horizontal planes, and a stabilizing plane mounted on a central horizontal axis extending in line with the vertical plane to be tilttable about said axis into the path of current discharge from between said converging planes.

8. An aeroplane comprising superposed horizontal planes converging toward each other at the prow and at the stern, a vertically disposed plane extending longitudinally of said superposed horizontal planes, a propeller mounted on either side of said vertical plane to work between said horizontal planes and in operation to take in an air current through the forward converging ends of said horizontal planes and to discharge the said current between the converging rear ends of said planes, a stabilizing plane mounted on a horizontal axis extending in line with said vertical plane and said stabilizing plane arranged to be tilttable into the path of current discharge from between said converging horizontal planes, and an altitude rudder at the prow end tilttable about a horizontal axis.

9. An aeroplane comprising a substantially horizontal plane, a carrying plane disposed below the horizontal plane and provided with an upwardly curved prow end, and a vertically disposed longitudinally extending plane arranged between said horizontal plane and said carrying plane.

10. An aeroplane comprising in combination, a rigid body comprising vertical planes extending upwardly and downwardly from a medial line of juncture and horizontal planes extending outwardly from said line of juncture, a carrying plane hung from said horizontal planes, propellers disposed between said carrying plane and horizontal planes upon opposite sides of said downwardly extending vertical plane, a prime mover on said carrying plane on one side of said downwardly extending vertical plane for operating said propellers, and an operator's seat on said carrying plane opposite the prime mover for counterbalancing the weight of the latter.

In testimony whereof I affix my signature in presence of two witnesses.

JOHN W. SWALES.
